United States Patent Office

Des. 180,643
Patented July 16, 1957

180,643

FOUR-WAY SCREW DRIVER

Clifford E. Fitch, Chicago Heights, Ill.

Application January 24, 1957, Serial No. 44,589

Term of patent 14 years

(Cl. D93—4)

Fig. 1.

Fig. 2.

Fig. 3.

Fig. 1 is a front elevational view of a four-way screw driver showing my new design;

Fig. 2 is a rear elevational view thereof;

Fig. 3 is a side elevational view thereof.

I claim:

The ornamental design for a four-way screw driver, as shown.
